UNITED STATES PATENT OFFICE

ELLIS M. PRESSNALL, OF PROCTOR, MINNESOTA
RERAILED RAILROAD EQUIPMENT

Application filed October 9, 1929. Serial No. 398,499.

My invention relates to a means and method for rerailing railroad equipment such as locomotives, tenders and cars which have been derailed.

5 In the rerailing of derailed locomotives and cars by the means and methods now commonly employed, there are a number of inherent disadvantages and objections which are not satisfactorily met in the usual types of equipment used, particularly the common rerailing frog. One of the principal objections to the frog is that the flange of the outer wheel must be raised above the rail with an attendant drop which, because of the great weight of the engine or car, proves injurious either to the rail or the engine or car equipment. This objection is overcome by my present invention wherein it is not necessary for the derailed wheels to be lifted above the top of the rails, but instead they are drawn up a smooth incline and run onto an abutting rail without any drop or shock whatever. The wheels or trucks are then run along temporary rail sections to the permanent track portion, and the rerailing operation is complete. By this means and method no jacks or auxiliary equipment are needed other than my improved replacer and possibly a switch point and a short rail section.

It is an object of my invention to provide an improved means and method of rerailing railway equipment.

35 It is another object of my invention to provide an improved type of replacer bar.

Another object of my invention is to provide a method of rerailing railway equipment, which is smooth, quick and efficient in operation.

Another object of my invention is to provide a rerailing replacer which is adapted to be used for either rail of the tracks.

45 Other objects and advantages will appear and be brought out more fully in the following specification, in which I refer to the accompanying drawings, wherein—

Figure 1 is a side view of a railway track section, showing my invention;

50 Figure 2 is a top view of the same; and

Figure 3 is a perspective view of the replacer bar embodying my invention.

Referring more particularly to the drawings, I show a railway track section having ties 10 and main rails 11. In Figure 3 I 55 show a replacer 12 having a base portion 13, an upper inclined portion 14 which substantially meets the base 13 at one end 15 and which terminates in a horizontal portion 16, at the opposite end. An abutting end portion 17 is formed at this end from which project jaws 18 which are separated from each other forming an aperture 19. Aperature 19 is substantially the width of the thickness of a standard track rail and jaws 60 18 have a vertical dimension substantially equal to the height of the rail web, and this jaw formation is such that the replacer can be placed at the end of a rail section with the jaws 18 on either side of the rail, and with portion 17 abutting the end of the rail, 65 portion 16 will be substantially on a level with the top of the ball of the rail. At the right in Figures 1 and 2 is shown dotted a car axle and wheels in approximately the 70 position as derailed, and the rerailing of the same is as follows:

The rail 20 adjacent the outer wheel is disconnected or cut at a point 21, and bent inwardly. A short rail section 22 is then 80 laid with one end abutting the end of the fixed rail 11 and spiked down. The replacer 12 is then brought into engagement with the opposite end of rail section 22, 85 with the end 15 approximately under the car wheel. For the opposite rail adjacent the inner wheel a switch point 23 is placed as shown, and likewise spiked down, and a replacer 12 secured to its butting end.

The locomotive or car can then be run 90 up incline 14 and the wheels passing portions 16, are run over the rail sections 22 and 23, and then onward to the permanent rails 11, with no dropping or bumping of any sort. The operation is smooth and easy and requires a minimum amount of effort and there is no likelihood of slipping or injury due to any jar, since there is no dropping from one level to another, as will be clear from the drawings. The same type of replacer 100

12 can be used on both rails and no other auxiliary equipment is necessary other than a switch point and a short rail section. It is clear that it is not necessary to raise the wheels of the locomotive or car above the bell of the rail, and it will be found that this type of rerailing device is especially useful on curves where the ordinary type of frog is inadequate and will not work.

Various changes and modifications in the design and construction of the illustrated device may be made without departing from the true scope of the invention as set forth in the appended claims.

5 I claim:

1. A replacer for rerailing equipment, comprising a base portion, a top portion, an inclined portion adjacent the top portion and terminating substantially with said base 20 portion, said replacer having means for engaging the end of a rail, said means comprising spaced abutments extending from an end of said replacer.

2. A replacer for rerailing equipment, comprising a base portion, a top portion, an inclined portion adjacent the top portion and terminating substantially with said base portion, said replacer having means for engaging the end of a rail, said means 30 comprising a pair of spaced jaws adapted to engage the web of the rail.

3. The herein described method of rerailing railway equipment comprising cutting one of the rails and bending the cut end inwardly, placing a rail section with an end abutting the remaining cut rail portion, securing an incline replacer adjacent the opposite end of the rail section, placing a switch point adjacent the opposite rail, securing an incline replacer to the extending end of said switch point, and drawing the car wheels up said replacer, over said rail section and switch point onto the main track rails.

45 4. The herein described method of rerailing railway equipment which consists of cutting a track rail and bending one of the cut sections inwardly, securing a rail section to the ties in abutting relation with the 50 other cut rail section, securing a switch point to the opposite rail opposite said rail section, and securing replacers to the abutting ends of said rail section and said switch point and in alignment with the car wheels, 55 and drawing or driving the car over said replacer, rail section, and switch point onto the main track rails.

Signed at Proctor, Minnesota, this 28th day of September, 1929.

ELLIS M. PRESSNALL.
